(74) Attorney, Agent, or Firm—Michael Best & Friedrich LLP

(57) **CLAIM**

We claim the ornamental design for a beverage glass identifying device, as shown and described.

DESCRIPTION

FIG. 1 is a perspective view of a beverage glass identifying device showing our new design;

FIG. 2 is a front view of FIG. 1;

FIG. 3 is a rear view of FIG. 1;

FIG. 4 is a right side view of FIG. 1;

FIG. 5 is a left side view of FIG. 1;

FIG. 6 is a top view of FIG. 1; and,

FIG. 7 is a bottom view of FIG. 1.

The broken lines in the drawings are for illustrative purposes only and form no part of the claimed design.
